UNITED STATES PATENT OFFICE.

CHARLES ERNEST JONES, OF CHICAGO, ILLINOIS.

DESIGN FOR A ROSETTE-CLAMP FOR LIGHT-REFLECTING BOWLS.

50,690.

Specification for Design.

Patented May 1, 1917.

Application filed March 6, 1917. Serial No. 152,937. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for a Rosette-Clamp for Light-Reflecting Bowls, of which the following is a specification, reference being had to the accompanying drawing, wherein—

Figure 1 is a side elevation, and Fig. 2 is a front elevation of a rosette clamp for light reflecting bowls, showing my new design.

I claim as my invention:

The ornamental design for a rosette clamp for light reflecting bowls, as shown.

CHARLES ERNEST JONES.
